CLARENCE W. MARSH, OF GREENWICH, CONNECTICUT.

ELECTROLYTIC CELL.

Application filed December 18, 1919. Serial No. 346,141.

To all whom it may concern:

Be it known that I, CLARENCE W. MARSH, a citizen of the United States, residing at Greenwich, in the county of Fairfield and 5 State of Connecticut, have invented certain new and useful Improvements in Electrolytic Cells, of which the following is a full, clear, and exact description.

This invention relates to electrolytic cells and particularly to those cells which employ a U, V, or similar shaped cathode. Cells of such shapes may be limited in their height because of the difficulty encountered in placing the diaphragm in position, which 10 difficulty is greatly increased when a cathode is employed which has formed therein a number of crimps or corrugations. To enable the insertion of a diaphragm in such cells, the cell body was necessarily made 15 wide enough to provide access to all parts of the interior so that the diaphragm could be carefully placed in position. The deeper the cell, the wider it had to be, and this greatly increased the weight of the cell and 20 the floor space occupied by it, without a corresponding increase in capacity.

An object of my invention is to provide a cell of the U, V, or similar shaped cathode type, in which the material required for its 25 construction, repair and renewal is reduced to a minimum.

Another object is to provide a cell of this type in which the anodes can be placed in position in a preferred arrangement before 30 the cells are assembled.

Another object is to provide a cell of this type which is sufficiently light and small to make practicable its suspension from supports.

40 Another object is to provide a cell of this type in which the renewal of the anodes or the changing of a diaphragm can be easily and quickly accomplished and while the cell is suspended.

45 Another object is to provide a cell of this type which occupies a minimum amount of horizontal area and which can be built substantially to any reasonable height without increasing the length or lateral space occupied.

In carrying out my invention I may construct my cell of two parts, or halves, by splitting it longitudinally along the central vertical axis, which parts, when the cell is 55 assembled, are detachably secured together in any suitable manner. Each half has an

anode and cathode compartment. While the two halves are separate, the anode, cathode and diaphragm of each half or part can be carefully and securely placed in position, 60 whereupon the halves or parts can be attached together and the cell is ready for use. When repairs are necessary the two halves or parts are separated, and either half or part can be repaired without hindrance from the other half. If a new diaphragm is necessary in one half, that can be supplied without disturbing the other half, thereby effecting a considerable saving in time and material over the prior constructions in which an entire new diaphragm was necessary if any change had to be made. If a crimped cathode is used, the diaphragm has to be carefully fitted in said crimps and secured therein before the anodes are placed in position. 70 In the old cells having the U, V, or similar shaped cathodes, this was practically impossible unless the cell body was made very wide, but in a cell constructed according to my invention the width or thickness can be 75 very small and the height may be comparatively very great.

I may also employ an ordinary cell casing and suspend therein a split cathode and diaphragm together with the anode. In this 80 case, the parts are first lifted from the casing and the cathode and diaphragm parts are separated, or replaced, as in the other embodiment above described.

I shall now describe the illustrated embodiments of my invention and shall thereafter point out my invention in claims.

Fig. 1 is a perspective of a cell constructed in accordance with my invention;

Fig. 2 is a perspective of one-half of such 95 a cell;

Fig. 3 is a transverse vertical section of a cell;

Fig. 4 is a horizontal section of a cell;

Fig. 5 is a transverse vertical section of 100 a modified form of cell, and

Fig. 6 is a transverse vertical section of another modified form of cell.

Referring more particularly to Figs. 1 to 4, the cell body comprises two complementary sections, each section having a side wall 1, end walls 2, and a bottom wall 3. The bottom walls may carry angle members 4 adjacent their abutting edges which members may be secured together in any 110 suitable manner as by bolts 5. The complementary end walls may be secured to

gether by bolts 6. Disposed along the side and bottom walls are a plurality of ribs 7 which may conveniently comprise channel members, which space the foraminous cathode 8 from the side and bottom walls to form a cathode chamber or compartment 9, from which the cathode liquid is withdrawn by means of an outlet 10. The cathode 8 may be plain, but it preferably is provided with horizontally extended crimps or corrugations which are substantially semi-cylindrical for a purpose to be hereinafter discussed. In front of the cathode and conforming in configuration thereto is 15 a diaphragm 11 of suitable material. The end walls are preferably provided with recesses 12 into which the end channels, cathode and diaphragm extend. Any suitable cementing or sealing material 13 is used to 20 fill the recess and seal the cathode and diaphragm in the end walls to hold the diaphragm in position against the cathode and also to prevent leakage between the cathode and anode chambers. The anode for each 25 section consists of a plurality of horizontally disposed rods 14 supported by the end walls 2 substantially at the center of curvature of the corrugations in the cathode and diaphragm. These rods may be electrically 30 connected in any suitable manner, and as shown it may be accomplished by a strip 15 connected to each rod 14, and in turn connected to one of the circuit wires leading to the cell. Any suitable cover 16 for the cell 35 may be employed and the cell may be suspended by means of an insulated support 17 and the hangers 18, the latter being secured to the ribs 7 or the walls of the cell. The cover is provided with an inlet 19 for brine, 40 or other liquid to be acted upon, and a gas exit passage 19a, and each of the cathode compartments is provided with an outlet pipe 20 for the removal of the hydrogen gas therefrom. When the cathode is provided with horizontal corrugations, the ribs 45 9 may be provided with inclined slots for receiving and supporting a plurality of deflecting strips 21 slightly under each corrugation or crimp so that any liquid which 50 percolates through the cathode will not run down the lower surface of the cathode but will be deflected to drop directly to the bottom of the cathode chamber. The provision of the deflecting plates is not essential but 55 they have been found useful.

When gas is liberated at the anode it tends to rise and is deflected in a circular direction by the corrugations. This induces a better local circulation of the electrolyte and this local circulation tends to carry the gas bubbles away from the anodes so that they will rise directly to the top of the electrolyte and not accumulate on or between the anodes and cathodes which are 65 disposed above to increase thereby the resist-

ance of the cell, or prevent contact of fresh electrolyte with the anodes. The cathode and diaphragm sections extend down over the abutting upturned ends of the bottom wall 3, and are clamped therebetween to seal 70 the anode chamber at the bottom when the two sections of the cell are brought together and secured. A suitable gasket 5^a may be provided between the angle members 4, if desired, to further seal the halves of the 75 cell when assembled.

In Fig. 5 I have illustrated a slightly modified cell having a cathode and diaphragm split into two parts which are clamped together by bolts 5^a, and clamping 80 strips 4^a, but in this embodiment the cathode 22 and diaphragm 23 are without crimps or corrugations. The anode 24 may conveniently comprise one member common to both of the sections, and the tank is illustrated as of one part, the split cathode being removable from the tank before being separated. I have illustrated the support for the cell as a pier 25 having insulation 26 thereon, but it is obvious that the cell can 85 be suspended instead if desired, as disclosed in the other modifications.

In Fig. 6 I have illustrated another form of cell having a V-shaped cathode 27 and diaphragm 28 to which my invention has 90 been applied. In this form, the cathode and diaphragm split as in the other embodiments, are without crimps or corrugations, and the anodes may comprise a plurality of spaced, horizontally disposed rods 10 or members 29, arranged parallel to the cathode so that the bubbles of the liberated gas will pass upwardly through the spaces between the rods or members 29 and thus directly to the exterior of the electrolyte 14 without accumulating on the upper anodes and thereby increasing the resistance of the cell and preventing contact of fresh electrolyte with the anodes. The passage of the bubbles of gas between the rods also induces 110 a local circulation which continually brings fresh electrolyte into contact with the anodes. The rods 29 are in this embodiment electrically connected by means of ribs 30 and lead posts 31. Each cathode chamber 115 is formed by the box made by the channel members 32 (instead of the ribs) and the enclosure is completed by the side walls 1 which are secured to the channel members. Angle members 4 which are secured to the 120 bottoms of the lower channel members and the bolts 5 serve to clamp the two parts of the cell and the split cathode and diaphragm together. Angle members 33 on the upper sides of the upper channel members are secured to the cover 35 by means of the bolts 34 which pass through the angle members 33 and the cover. The cell is suspended by 125 means of the insulated hanger 36.

The top and the end walls of each of the 130

modifications may be of any suitable material such as soapstone or concrete, and the cells of Figs. 5 and 6 have the usual outlets for the caustic liquid, and hydrogen and 5 chlorine gas. One of the end walls of each cell may be provided with a suitable gage 37 to indicate the height of the liquid in the cell.

It is obvious that various other modifications may be made in the construction of my 10 apparatus as illustrated in the drawings and above particularly described, within the principle and scope of my invention.

I claim:

15 1. In an electrolytic cell, a cathode comprising two parts adapted to be joined together to form an anode compartment, a body portion comprising two parts, each body part carrying one of the cathode parts 20 and forming therewith a cathode compartment, a diaphragm and an anode carried by each body part, and securing means for detachably connecting the body portions together and thus unite the cathodes to complete the anode compartment.

25 2. An electrolytic cell comprising a cathode divided into two parts, a diaphragm divided into two parts, one of the diaphragm parts lying against the inner face of each of 30 the cathode parts, a cell body comprising two complementary parts one of which carries each of the cathodes, an anode carried by each part of the cell body in spaced relation to the diaphragm and cathode, and securing 35 means for connecting the parts of the cell body together and clamping the diaphragm and cathode parts together.

3. An electrolytic cell comprising a body having two separable complementary parts, 40 a split cathode and a split diaphragm carried by the parts and each adapted to be united by the joinder of the complementary parts.

4. An electrolytic cell comprising a split 45 cathode, whose parts are detachably secured together, and a split diaphragm whose parts are united by the joinder of the parts of the split cathode.

5. An electrolytic cell comprising a substantially continuous cathode, split along its 50 lower portion, and a split diaphragm having its parts united by the joinder of the parts of the split cathode.

6. An electrolytic cell comprising a substantially continuous cathode split along its 55 lower portion, diaphragms lying in front of said cathode parts and having their lower ends clamped together by said split cathode.

7. An electrolytic cell comprising two 60 complementary parts, each part carrying a cathode, a diaphragm and an anode, and means for detachably uniting said complementary parts.

8. An electrolytic cell comprising two 65 complementary parts, each part carrying a

cathode spaced therefrom to form a cathode compartment, a diaphragm in front of said cathode, and an anode spaced from the diaphragm and cathode, and means for detachably uniting said complementary parts to form an anode compartment.

9. An electrolytic cell comprising two cathode members adapted to be secured together at their lower ends to form an anode compartment, a diaphragm on the inner face 75 of each cathode and having its lower end clamped between the two cathode members, a casing having two complementary parts, each part of the casing carrying one of the cathode members and an anode, and securing 80 means for detachably uniting the casing parts, diaphragms and cathodes.

10. An electrolytic cell comprising two complementary parts, each part having a side wall, two end walls and a bottom wall, 85 ribs extending along the side and bottom walls, a cathode disposed adjacent the ribs and spaced thereby from the side and bottom walls to form a cathode compartment, a diaphragm disposed in front of the cathode and conforming in configuration thereto, anodes carried by the end walls in front of the diaphragms, and means for sealing the ends of the diaphragm and cathodes 95 against the end walls and for holding the diaphragm to conform with the configuration of the cathode.

11. An electrolytic cell comprising two complementary parts, each part having a side wall, two end walls and a bottom wall, 100 ribs extending along the side and bottom walls, a cathode disposed adjacent the ribs and spaced thereby from the side and bottom walls to form a cathode compartment, a diaphragm disposed in front of the cathode and conforming in configuration thereto, anodes carried by the end walls in front of the diaphragms, means for sealing the ends of the diaphragm and cathodes 105 against the end walls and for holding the diaphragm to conform with the configuration of the cathode, and means for suspending the cell from the ribs.

12. An electrolytic cell comprising a substantially U-shaped cathode of two parts adapted to be united to form an anode chamber, and a diaphragm of two parts adjacent the cathode and having its parts united by the joinder of the parts of the cathode.

13. An electrolytic cell comprising a substantially U-shaped cathode having a split along the bend thereof, the two parts being detachably secured together, a substantially U-shaped diaphragm adjacent the cathode and similarly split along the bend thereof, 115 the split ends of the diaphragm being clamped between the parts of the cathode.

14. An electrolytic cell comprising a cathode of two parts, uniting means for the cathode parts, a diaphragm of two parts dis- 120

posed on the interior of the united cathode and having the adjacent ends clamped between the united portions of the cathode.

15. An electrolytic cell comprising a sectional casing, and a divided cathode and anode, the divisions being carried by the sections of the casing.

16. An electrolytic cell comprising a sectional casing, a horizontally crimped cathode carried by each section, and anode members carried by each section and disposed each concentrically with the surface of a crimp of the cathode.

17. An electrolytic cell comprising a V shaped sectional casing having the sections corresponding to the arms of the V separable, a split cathode clamped between the sections of the casing, and anode members

disposed between and parallel to the cathode sections.

18. An electrolytic cell comprising a sectional casing, a divisible cathode and a divisible diaphragm clamped between the sections of the casing, and anodes disposed between the cathode sections.

19. In an electrolytic cell, a casing, a divided cathode suspended from the upper end of the casing, a diaphragm clamped between the divisions of the cathode, a closure for the casing and an anode suspended from the closure within the diaphragm and in spaced relation thereto.

In witness whereof I hereunto subscribe my signature.

CLARENCE W. MARSH.
